UNITED STATES PATENT OFFICE

142,641

DESIGN FOR AN INDUSTRIAL TRUCK OR SIMILAR ARTICLE

George V. Johnson, Portland, Oreg., assignor to
Willamette Hyster Company, Portland, Oreg.,
a corporation of Oregon

Application November 16, 1943, Serial No. 111,703

Term of patent 14 years

(Cl. D14—3)

To all whom it may concern:

Be it known that I, George V. Johnson, a citizen of the United States, and a resident of Portland, in the county of Multnomah, State of Oregon, have invented a new, original, and ornamental Design for an Industrial Truck or Similar Article, of which the following is a specification, reference being had to the accompanying drawings, forming a part thereof.

Figure 1 is a side elevational view of an industrial truck showing my new design.

Figure 2 is a front elevational view of the industrial truck shown in Figure 1.

Figure 3 is a rear elevational view of the industrial truck shown in Figures 1 and 2.

Figure 4 is a top plan view thereof.

The side of the device opposite that shown in Figure 1 of the drawings is substantially the same as illustrated.

I claim:

The ornamental design for an industrial truck or similar article, substantially as shown and described.

GEORGE V. JOHNSON,
